UNITED STATES PATENT OFFICE.

EDWARD F. SMITH, OF CINCINNATI, OHIO, ASSIGNOR TO THE NEIL & SMITH ELECTRIC TOOL CO., OF CINCINNATI, OHIO, A CORPORATION OF OHIO.

MANUFACTURE AND CONSTRUCTION OF COMMUTATORS.

1,195,861.

Specification of Letters Patent. Patented Aug. 22, 1916.

Application filed July 16, 1914. Serial No. 851,389.

To all whom it may concern:

Be it known that I, EDWARD F. SMITH, residing at Cincinnati, Hamilton county, State of Ohio, have invented certain new and useful Improvements in the Manufacture and Construction of Commutators, of which the following is a clear, full, and exact description, attention being called to the drawing which accompanies this application and forms a part thereof.

This invention concerns the construction and manufacture of devices known as commutators and forming adjuncts of certain types of generators and dynamos. They consist of segments assembled side by side and radially disposed around a common center so as to form a cylindrical body which is adapted to be mounted upon a shaft, each segment being insulated from the other and from said shaft. A so-called brush, another adjunct, is used in connection with these commutators, it being held in yielding contact with the outer, cylindrical side thereof and while one of these devices rotates with reference to the other one. It is desirable that this contact be a perfect one and without the slightest interruption, otherwise "sparking" results which is very objectionable because destructive to the commutator and to the brushes. Such interruptions result when the surface of the commutator which is in contact with the brushes is not cylindrically true, if insulating material and segments do not wear away equally, leaving ridges, or if the segments with the insulating material between them are not so firmly held together as to form an absolutely rigid body. Either one of these conditions produces vibrations of the brushes whereby temporarily their contact is interrupted, causing the gap to be bridged by the objectionable spark.

The object of my invention is to construct commutators in a manner whereby the various segments are firmly held together so as to form with the insulating material between them a solid mass, homogeneous and integral for all practical purposes and to present a brush-contact surface which wears equally in all its parts and remains therefore cylindrical at all times.

The invention consists of the method of producing commutators in the manner aforesaid and of the commutator itself and constructed in accordance with this method.

In the following specification and claims

is found a full description of my invention, its parts, and the manner in which it is practised, all of which is illustrated in the accompanying drawing in which:

Figure 1 shows (in perspective view a block of metal to be used in the production of a commutator according to my plan. Fig. 2 shows a commutator blank formed out of this block. Fig. 3 is a vertical cross section on a plane indicated by numerals 3-3 shown in Fig. 2. Fig. 4 in a sectional view shows an apparatus whereby the aforesaid blank is acted upon in a certain manner. Fig. 5 in a view similar to Fig. 2, shows appearance of the blank after having been acted upon by the apparatus shown in Fig. 4. Fig. 6 also a similar view, shows the blank further advanced in the state of its manufacture. Fig. 7 is an axial section of the completed commutator.

In the drawing, Fig. 1, shows suitable metal preferably copper which is used in my improved manufacture of commutators and in a preliminary shape which may be the form of a cylindrical block 10. This block, by suitable machine tool operation, is further shaped so as to have a central bore 11, countersunk recesses 12, 12 in its opposite flat sides and radially arranged cuts 13 which extend in from the peripheral side toward said bore. These cuts are all of practically equal depth and terminate so as to leave an intact annular zone of metal 14 around said bore so that a blank results as shown in Figs. 2 and 3. This blank is now placed within a cylinder 15 and with one of its flat sides upon a base 16 as shown in Fig. 4. Dielectric material 17, in plastic condition, is placed upon the blank within the cylinder and by means of a plunger 18 this material is forced against said blank so as to enter all open parts of the same, particularly cuts 13, the object being to fill these latter completely. Material in excess of that really required is used and cylinder 15 rests loosely upon base 16, so that the surplus may disgorge from below the lower edge of the cylinder, this latter being lifted by the reaction. This impressing of material may be repeated until all of the cuts 13 and each one of them are thoroughly filled and packed. The blanks are now removed from cylinder 15, surplus material, especially that which fills bore 11 and recesses 12-12, is removed and they are set aside

2
to permit the material to harden. This may be effected by air-drying, if there is sufficient time; otherwise the use of artificial heat will be resorted to. Next the blanks 5 while secured in a suitable holding device are rebored to remove the metal 14 within bore 11 from which action finally a structure results as shown in Figs. 6 and 7, and composed of segments 19, all insulated 10 from each other by material 17 whereby they are also held together. A usual bushing, to form a bearing for the commutator and consisting of two complementary members 21 and 22, is finally placed into bore 15 11 and recesses 12-12. It is insulated from the commutator by washers 23. Material 17 in addition to being dielectric should be also 20 inert and neutral with reference to the action of acids or alkalis and so as not to be susceptible to the action of grease, oil or water, nor affected by heat. Pulverized asbestos or mica mixed with a suitable binder are preferable materials. I use pulverized mica formed into a plastic mass by means 25 of silicate of soda. Whiting is added to overcome the porosity of the mica which would reduce the density of the mass and render it more or less elastic. This mass by being applied in the manner stated automatically 30 fills cuts 18 completely, no matter whether they are perfect or not, that is whether their sides are truly parallel, irregular or uneven. The plastic mass fills in 35 everywhere and as a result forms with the segments a solid and rigid body and in which the segments are firmly held against vibration. As against the use of mica in sheet form, the advantage is obvious because the sheets do not hold the segments to each 40 other, nor do they in all cases completely fill the spaces between the segments because, being of rigid substance and of fixed thickness, they cannot adjust themselves to irregularities in the shape of the segments or 45 in the surface of the sides thereof, nor to differences in the size of the spaces between them. As a result neither the segments nor

the material between them are held rigid, spaces result between them, they do not form a compact body, segments may move 50 and possibility of vibration exists. Furthermore, in applicant's case, the material is of a granular texture, and wears away even with the free outer ends of the segments 55 so that no high spots or ridges result.

The apparatus for applying the insulating material may be of a size to admit a number of blanks, superposed, or side by side, so that a number of them may be acted 60 upon. By properly gaging the quantity of the mass, the operation may consist of one operation of the plunger or several charges may be applied.

Having described my invention, I claim 65 as new:

1. The method of manufacturing commutators which consists of producing an integral cylindrical blank of metal which contains the metal for the segments and is provided with radially disposed spaces between the metal intended for said segments, of filling these spaces with insulating material and of removing the metal at the inner ends 70 of these filled spaces so as to completely 75 separate the segments from each other.

2. The method of manufacturing commutators which consists of producing an integral cylindrical blank of metal which contains the metal for the segments and is provided with radially disposed spaces between the metal intended for said segments, of filling these spaces with insulating material and of axially boring out said blank, the bore being of an extent to reach into the inner 80 ends of the filled spaces so as to completely 85 part the segments from each other.

In testimony whereof, I hereunto affix my signature in the presence of two witnesses.

EDWARD F. SMITH.
